(57) **CLAIM**

The ornamental design for a modular forend system for tactical firearms, as shown and described.

DESCRIPTION

FIG. 1 illustrates a perspective, side view of a new design for a modular truss-type forend system for tactical rifles depicting a modular forend with a plurality of accessory mounting rails;

FIG. 2 illustrates a front view of a new design for a modular truss-type forend system for tactical rifles depicting a modular forend with a plurality of accessory mounting rails;

FIG. 3 illustrates a rear view of a new design for a modular truss-type forend system for tactical rifles depicting a modular forend with a plurality of accessory mounting rails;

FIG. 4 illustrates a side view of a new design for a modular truss-type forend system for tactical rifles depicting a modular forend with a plurality of accessory mounting rails;

FIG. 5 illustrates a side view of a new design for a modular truss-type forend system for tactical rifles depicting a modular forend with a plurality of accessory mounting rails;

FIG. 6 illustrates a top view of a new design for a modular truss-type forend system for tactical rifles depicting a modular forend with a plurality of accessory mounting rails; and,

FIG. 7 illustrates a bottom view of a new design for a modular truss-type forend system for tactical rifles depicting a modular forend with a plurality of accessory mounting rails.

The broken, dashed lines shown in the various figures depicting the invention are included for the purpose of illustrating environment and do not form any part of the claimed design.
